UNITED STATES PATENT OFFICE.

LOUISE L. HEUSTIS, OF NEW YORK, N. Y., ASSIGNOR TO THE CORPORATION OF J. H. JOHNSTON & COMPANY, OF SAME PLACE.

DESIGN FOR A BOOK-MARK.

SPECIFICATION forming part of Design No. 23,060, dated February 13, 1894.

Application filed November 6, 1893. Serial No. 490,163. Term of patent 3½ years.

To all whom it may concern:

Be it known that I, LOUISE L. HEUSTIS, a citizen of the United States, residing at 400 West Fifty-seventh street, New York, in the county 5 of New York and State of New York, have invented and produced a new and original Design for a Combined Book-Bookmark and Paper-Cutter; and I do hereby declare the following to be a full, clear, and exact description of the 10 invention, such as will enable others skilled in the art to which it appertains to make and use the same, reference being had to the accompanying drawing, and to letters of reference marked thereon, which form a part of 15 this specification.

The single figure in the drawing is deemed to be sufficient to fully illustrate the design, the same being a front elevation of the newly shaped paper cutter and book mark.

20 The leading feature of the design consists in the shape or configuration of a book-mark substantially as shown and hereinafter described, and finally embodied in the claim.

In said drawing, A indicates the blade-shaped paper cutter, B the ornamental clip, 25 between which and the blade shaped part, the leaves of the book are held, and C indicates the handle which is shaped in resemblance to a boy, dressed as a page of the chivalric period and in the act of making an obeisance. 30

Between the handle and the blade-shaped part is a transverse bar-shaped part, d, and the said blade-shaped part is ornamented with panels e, e, or like spaces for an inscription. 35 The general outline of the article is in resemblance to that of a dagger.

What I claim as new is—

The design for a book mark, substantially as herein shown and described. 40

In testimony that I claim the foregoing I have hereunto set my hand this 28th day of September, 1893.

LOUISE L. HEUSTIS.
